A. T. DE WITT.

SWITCH OPERATING MECHANISM,
APPLICATION FILED MAY 18, 1916.

1,252,329.

Patented Jan. 1, 1918.

FIG. 1.

Arthur T. De Witt

UNITED STATES PATENT OFFICE.

ARTHUR T. DE WITT, OF FORT WAYNE, INDIANA, ASSIGNOR, BY DIRECT AND MESNE ASSIGNMENTS, OF TWO-THIRDS TO FRED L. DE WITT AND ONE-THIRD TO M. SCHIFFER, BOTH OF CHICAGO, ILLINOIS.

SWITCH-OPERATING MECHANISM.

1,252,329.

Specification of Letters Patent.

Patented Jan. 1, 1918.

Application filed May 18, 1916. Serial No. 98,467.

To all whom it may concern:

Be it known that I, ARTHUR T. DE WITT, a citizen of the United States, residing at Fort Wayne, in the county of Allen and 5 State of Indiana, have invented certain new and useful Improvements in Switch-Operating Mechanism, of which the following is a specification.

The present invention has to do with improvements in switch operating mechanism of the general type or classification of that shown in Letters Patent of the United States, No. 908,756, issued to me January 5, 1909, for improvements in switch operating 15 mechanism. The present invention, however, has to do with certain improvements and features of invention not shown or disclosed in the aforesaid Letters Patent.

I may further state at this point that the 20 present invention relates to improvements in switch operating mechanism of that type in which the switch can be thrown automatically from the car and without the necessity of stopping the car, thereby dispensing with the services of a switchman who would otherwise be required for throwing the switch.

One of the objects of the invention is to 25 simplify the construction of a device of this type, while at the same time giving it such mechanical construction and principles of operation that it will be positive and definite in its action.

In this connection another object is to 30 lower the cost of manufacture and construction of the switch and eliminate as far as possible the liability to mechanical derangement in service.

Other objects and uses of the invention 35 will appear from a detailed description of the same which consists in the features of construction and combinations of parts hereinafter described and claimed.

In the drawing: 40 Figure 1 shows a longitudinal section through the switch operating mechanism, being taken on the lines *m-n* and *o-p* indicated on Fig. 2, looking in the direction of the arrows;

Fig. 2 is a top view of the two boxes containing the main operative parts, the covers being removed; and

Fig. 3 is a detail plan view of the roller carried by the car, and which serves to op-

erate the switch from the car and under the 55 control of the motorman or other person on the car.

Referring now to the drawing, and particularly to Fig. 2, the switch is designated by the letter *E*. The switch point of this 60 switch is designated by the letter *h*. Located in the street pavement or right of way at a point adjacent to the switch is an operating box *A* containing certain operative mechanisms. In advance of the switch is 65 another operating box *B* which is also located in the pavement or permanent structure of the right of way. A tube or pipe or the like *C* joins together the interior portions of the boxes *A* and *B* and carries 70 an operative connection which extends between them. It will be understood that the covers have been removed from the boxes *A* and *B* so as to expose or reveal their interior construction. 75

Within the box *A* is a double cam member *e* having a central point *e'* and two side wings *e²* and *e³* respectively. This double cam is pivoted in its central portion at the point *e'* shown in Fig. 1, so that, as it is 80 swung in the one direction or the other, its rear end *e⁵* will be thrown back and forth.

Behind this double cam is a lever or the like *f* pivoted to the point *f'*. A pin *f²* extends upwardly from the rear end *e⁵* of the double cam *e* and engages a slot or recess in the lower face of the lever *f*, so that the said lever is swung back and forth in the one direction or the other by the movements of the double cam. A link *g* has one end 85 connected to the free end of the lever at the point *f³*, and its other end connected to the switch point at the point *f⁴*. Consequently, the switch point will be thrown back and forth according to the movements of the 90 double cam. With the parts shown in the full line position of Fig. 2, the switch point stands in the position for the main line of the track. Upon swinging the double cam into the dotted line position shown in said 95 figure, the switch point will be drawn back into the dotted line position indicated.

The movements of the double cam are effected through the instrumentality of a finger *d* which can be forced back and forth. 100 This finger is pivoted at the point *d'* to one end of a rod *c* extending from the operating box *B* through the pipe or tube *C*. Upon re-

tracting the rod C, the finger always assumes the central position shown by the full lines in Fig. 2, and it will swing the double cam *e* into the position reverse from that which it 5 formerly occupied. This is because the swinging of the double cam will carry the central point *e'* to one side or the other of the position occupied by the finger *d*.

Within the operating box B is a plate *a* 10 pivoted at the point *a'*. The upper portion of this plate extends somewhat above the upper surface of the box, and also a slight distance above the street level, so that it is exposed to the operation of the roller D. 15 This roller is carried on the lower end of an arm D' which is a portion of the equipment of the car, and normally stands in raised position elevated sufficiently to insure that the roller D will clear the upper edge of the operating plate *a*. Upon depressing the arm 20 and roller, the roller will be thrown down, so that it will strike against the point *a²* of the operating plate *a*, so as to throw the same forward against the force of the spring b. The rear end of the rod *c* is pivoted to 25 the plate *a* at the point *k*, so that the swinging of the plate will automatically swing the double cam *e* through the instrumentality of the finger *d*. As soon as the arm and 30 roller have passed away from the plate *a*, the same will be retracted by the spring *b*.

It is to be observed that the cover plates for the boxes A and B are shown in position in Fig. 1.

35 I claim:

1. In a device of the class described, the combination with a switch point and an operating arm carried by a vehicle traveling toward the switch point, there being a contacting roller on the lower end of said arm, 40 of an operating box adjacent to the switch point, another operating box in advance of the switch point, a double cam member pivotally mounted in the first mentioned operating box to swing on a vertical pivot, said 45 double cam member having a central tooth and a pair of side cam faces, a lever pivotally mounted in said operating box to swing on a vertical pivot behind the double cam 50 member, an operating connection from the double cam member to the lever for swinging the lever in direction opposite to the direction of movement of the double cam member and simultaneously therewith, a link 55 connection from said lever to the switch

point, a hollow tubular member connecting the operating boxes together, an operating plate pivotally mounted in the other operating box to swing about a horizontal pivot, said plate having a tooth projecting above 60 the upper surface of said operating box, a finger mounted in the front portion of the first mentioned operating box in position to strike the double cam member when said finger is forced backwardly, a link connection 65 extending through the pipe and joining the finger to the operating plate, and a spring normally retracting the operating plate, link connection, and finger, the aforesaid contacting point lying in position for engagement by the roller of the operating lever 70 when said lever is depressed, substantially as described.

2. In a device of the class described, the combination with a switch point and an operating lever carried by a vehicle traveling toward the switch point, there being a contacting portion on the lower end of said lever, of an operating box adjacent to the switch point, another operating box in advance of the switch point, a double cam pivotally mounted in the first mentioned operating box to swing about a vertical pivot, an operative connection from said double cam to the switch point for the purpose of moving the switch point back and forth according to the movements of the double cam, an operating plate in the second mentioned operating box, said plate being pivoted to swing about a horizontal pivot, and having 80 a contacting portion extending above the operating box wherein it is mounted and adapted for engagement by the contacting portion of the lever when the same is lowered into operative position, an oscillatable 85 finger in the first mentioned operating box mounted in position to engage the double cam member and throw the same in one direction or the other, an operative connection from said finger to the operating plate, and a spring normally retracting the operating plate into inoperative position, substantially 90 as described.

In testimony whereof I have hereunto set my hand in the presence of two witnesses. 105

ARTHUR T. DE WITT.
